(57) **CLAIM**

The ornamental design for a nib for electronic pen, as shown and described.

DESCRIPTION

FIG. 1 is a bottom front perspective view of a nib for electronic pen showing my new design;

FIG. 2 is a front elevation view thereof, wherein the rear elevation view, right side elevation view, and left side elevation view are the same as the front elevation view;

FIG. 3 is a bottom plan view thereof;

FIG. 4 is a top plan view thereof;

FIG. 5 is a reduced size front elevation view thereof;

FIG. 6 is a bottom front perspective view of another embodiment of the nib for electronic pen of FIG. 1;

FIG. 7 is a front elevation view thereof, wherein the rear elevation view, right side elevation view, and left side elevation view are the same as the front elevation view;

FIG. 8 is a bottom plan view thereof;

FIG. 9 is a top plan view thereof; and,

FIG. 10 is a reduced size front elevation view thereof.

The broken lines shown in FIGS. 5, 6, 7, 9, and 10 illustrate environmental subject matter and form no part of the claimed design.
